UNITED STATES PATENT OFFICE.

WILLARD W. SAWYER, OF NEW YORK, N. Y., ASSIGNOR TO THE SAWYER-BOSS MANUFACTURING COMPANY, OF SAME PLACE.

NUMBERING-MACHINE.

SPECIFICATION forming part of Letters Patent No. 654,676, dated July 31, 1900.

Application filed May 8, 1900. Serial No. 15,938. (No model.)

To all whom it may concern:

Be it known that I, WILLARD W. SAWYER, a citizen of the United States, residing at New York, (Brooklyn,) in the county of Kings and State of New York, have invented a certain new and useful Improvement in Numbering-Machines, of which the following is a specification, reference being had to the accompanying drawings.

- 16 This invention relates to that class of hand numbering-machines in which there are a series of similarly-spaced numbering-wheels and a like series of ratchet-wheels, to operate which a lever is provided, which lever, in addition to consecutively moving the numbering-wheels automatically, slightly depresses the inking-pad immediately before the numbering-wheels are turned in order that the pad may not be injured by the sharp type on said wheels; and the invention consists in the peculiar construction, arrangement, and combinations of parts hereinafter more particularly described and then definitely pointed out in the claims at the end hereof.
- 25 In the accompanying drawings, which represent the preferable embodiment of my invention, Figure 1 is a side elevation of my numbering-machine with part of the frame thereof broken away to better show the working parts. Fig. 2 is a similar view thereof with the hand-lever slightly depressed in order to move the pad away from the type on the numbering-wheels. Fig. 3 is a perspective view of the operating-lever detached. Fig. 35 4 is a bottom plan, and Figs. 5 and 6 are details.

Referring now to the details of the drawings, 1 represents the main frame in which slides the tubular plunger 2, to which is attached the fork 3, carrying the numbering-wheels 4 and their ratchet-wheels 5, the said tubular plunger 2 being provided with a spiral spring 6 and the usual locking-pin 7 and head 8, all of which may be made of similar form to many stamps now in use.

50 Integrally formed on the fork 3 and projecting in opposite directions are the guiding-flanges 9, which slide in similarly-shaped grooves 9^a in the main frame 1 in order to guide the numbering-wheels as the frame is reciprocated vertically. An ink-pad frame

10 is pivotally connected at 11 to the main frame 1, and this inking-pad frame is also pivotally connected to the fork 3 by means of the links 12, one of which is on each side of the fork. This inking-pad frame is of the usual construction and is so formed that as the head is depressed by the hand of the operator to depress the spindle and fork the inking-pad is automatically swung away from the type-wheels to allow the latter to print, and on the reverse movement of the frame carrying the numbering-wheels this inking-pad is automatically returned with its pad contacting with the type.

65 The numeral 13 represents a frame-like lever pivotally connected to the fork 3 at 14 and carrying at one end an operating handle or lever 15 and at the other end a pawl-carrier 16, these parts being so formed that as the lever is moved toward the handle the pawls are caused to move the numbering-wheels in order to bring a new number or numbers into printing-line. This frame 13 is formed with integral seats or sockets 17, 70 one of which is on each side of said frame and substantially in line with a line drawn through the center of the machine. Push-rods 18 are provided having preferably cone-shaped heads 18^a, which fit in the aforesaid seats or 75 sockets 17, the other ends of said push-rods projecting through perforations in the flanges 9 of the fork 3 and contacting with lugs 10^a, formed on the inking-pad frame. Spiral springs 19 are provided which are slipped 80 over push-rods 18 and act between the cone-shaped heads 18^a and the flanges 9 and serve the double purpose of holding these push-rods in position and of returning the lever 15 to its normal position after it has been shifted 85 by the operator.

90 From the above description and accompanying drawings it will be seen that when the handle or lever is depressed to move a numbering-wheel the ends of the push-rods 18 act 95 on the heads 18^a of the inking-pad frame, and thereby push the latter away from contact with the type.

It is obvious that the push-rods 18 may operate on the inking-pad frame itself, thereby dispensing with the lugs 10^a, and the push-rods themselves may be made integral with

the frame 13, if it is so desired, in which case it will be necessary to form slots instead of perforations in the flanges 9 of the fork 3. The frame-like lever 13 is preferably formed 5 with the strengthening rod or spindle 13^a, and while this rod or spindle greatly adds to the strength of said frame-like lever it may be omitted if desired. It is also manifest that other changes may be made without de- 10 parting from the spirit of my invention.

Having shown what I consider the preferable way of carrying out my invention, but without limiting myself to the exact constructions described and shown, what I claim as 15 new is—

1. The combination in a numbering - machine and with the inking-pad thereof, of a fork slidingly mounted in the main frame and carrying numbering and ratchet wheels, 20 a frame pivotally connected with said fork and provided with an operating-lever near one end and pawls near the other end, and a push-rod projecting from said frame and co-acting with said inking-pad and pushing the 25 latter away from the type as the said lever is depressed.

2. The combination in a numbering - machine and with the inking-pad thereof, of a fork slidingly mounted in the main frame 30 and carrying numbering and ratchet wheels, a frame pivotally connected with said fork and having an operating-lever near one end and carrying pawls near its other end, a push-rod projecting from said frame and coacting

with said inking-pad, and a spring arranged 35 to operate said lever in one direction.

3. The combination in a numbering - machine and with the inking-pad thereof, of a fork slidingly mounted in the main frame and carrying numbering and ratchet wheels, 40 a frame pivotally connected with said fork and having an operating-lever and pawls for operating said numbering and ratchet wheels, a push-rod projecting from said frame and co-acting with said inking-pad, and a spring 45 slipped over said push-rod and arranged to operate said lever in one direction.

4. The combination in a numbering - machine and with the inking-pad thereof, of a fork slidingly mounted in the main frame 50 and carrying numbering and ratchet wheels, a frame pivotally connected with said fork and having an operating-lever and pawls for engaging said ratchet-wheels, a seat or socket formed on said frame, a push-rod having a 55 head engaging said seat or socket and its opposite end coacting with said inking-pad, and a spring slipped over said push-rod and arranged to hold said push-rod in position and also to operate the aforesaid lever in one di- 60 rection.

In testimony whereof I affix my signature, in the presence of two witnesses, this 3d day of May, 1900.

WILLARD W. SAWYER.
